UNITED STATES PATENT OFFICE.

ALFRED T. BALCH, OF BROCKTON, MASSACHUSETTS, ASSIGNOR TO H. F. CRAWFORD MANUFACTURING COMPANY, OF BROCKTON, MASSACHUSETTS, A CORPORATION OF MASSACHUSETTS.

SHANK STIFFENER FOR SHOE SOLES.

Application filed January 2, 1923. Serial No. 610,149.

To all whom it may concern:

Be it known that I, ALFRED T. BALCH, a citizen of the United States, residing at Brockton, in the county of Plymouth and 5 State of Massachusetts, have invented new and useful Improvements in Shank Stiffeners for Shoe Soles, of which the following is a specification.

This invention relates to a shank stiffener 10 of spring steel, interposed between the shank portions of the outsole and insole of a shoe, and having sufficient resilience to permit the required flexure of said shank portions in walking, and to normally maintain said 15 shank portions at the desired curvature when they are not subjected to flexing stress.

The invention is embodied in a stiffener composed of an outer member contacting with the outsole, and adapted to slidably 20 engage a securing member on the insole, and an inner member contacting with the insole, said members being inseparably connected, and adapted to be independently flexed, so that the outer member is adapted to conform 25 independently to flexures of the shank portion of the outer sole, and the inner member constitutes an independently flexible yielding support for the shank portion of the insole.

30 Of the accompanying drawings forming a part of this specification,—

Figure 1 is a bottom plan view of a portion of a shoe having a shank stiffener embodying the invention, before the application 35 of the outsole.

Figure 2 is a section on line 2—2 of Figure 1, the outsole being shown by dotted lines.

40 Figure 3 is a perspective view of the stiffener.

The same reference characters indicate the same parts in all the figures.

45 My improved stiffener is adapted for use with a shoe, the insole *a* of which has a securing member, such as a bifurcated rivet *b*, inserted in the insole, as shown by Figure 2, the head of the rivet being flush with the upper surface of the insole, and the bifurcations of its shank being bent below 50 the lower surface to form ears *c*, *c*, which project in opposite directions and are slightly spaced from the under surface of the inner

sole, as shown by the Crawford Patent, No. 1,029,278, dated June 11, 1912.

The stiffener comprises a resilient outer 55 member 12, which is a thin steel strip, having in its forward end a slot 13, adapted to receive the shank of the rivet *b*, the arrangement being such that the forward end of the member 12 is adapted to slide between 60 the ears *c* and the bottom surface of the insole, as described in the Crawford patent. The opposite end portion of the member 12 may be provided with an orifice 14, adapted to receive a tack 15, driven into the insole, 65 as shown by Figure 2.

The member 12 is curved, to conform to the normal curvature of the shank portion of an outsole *d*.

The stiffener also comprises a resilient inner member 16, which is also a thin strip of 70 steel, and has a more abrupt curvature than the outer member 12, the end portions of the inner member bearing on corresponding portions of the outer member. The inner member 75 is spaced between its end portions from the outer member, as shown by Figure 2.

The members 12 and 16 are inseparably connected by connections between their end portions, permitting independent flexure of 80 each member, so that the outer member is adapted to conform independently to flexures of the shank portion of the outsole, and the inner member constitutes an independently flexible yielding support for the shank 85 portion of the insole.

Said connections are preferably embodied in headed rivets 17, fixed to one of the members, and passing through the end portions of the other member, the last-mentioned 90 member being slotted to permit independent flexure of each member.

In this instance I show the rivets 17 fixed to the outer member 12, and passing through slots 18 in the inner member, each rivet having a head at one end bearing on one of the members, and an upset end forming another head bearing on the other member.

When the shoe is flexed, as in the act of walking, the outer member is adapted to conform to the flexure, its slotted end sliding in contact with the securing member *b*, and its ears *c*. The inner member 16 may be flexed 100 with the outer member, and is independently

flexible and adapted to be pressed at its central portion toward the outer member by the weight of the wearer, the slots 18, and the rivets 17, permitting the described flexures of each of said members.

It will be seen that the inner member 16 constitutes an arch support, which conforms to changes of form of the arch of a human foot, the curvature of the inner member being reduced by an increase of pressure thereon, and restored to normal when the pressure is removed.

It is obvious that one slot 18 may be provided, instead of two.

15 I claim:

1. A shank stiffener comprising a resilient outer member, curved to conform to the normal curvature of the shank portion of an outsole, and provided in its forward end with 20 a slot, adapted to have a sliding engagement with a securing member fixed to an insole; and a resilient inner member having a more abrupt curvature than the outer member, and bearing at its end portions on the outer member, said inner member being spaced, between its end portions, from the outer member, and connections between the end portions of said members permitting independent flexure of each member, so that the

outer member is adapted to conform independently to flexures of the shank portion of the outsole; and the inner member constitutes an independently flexible yielding support for the shank portion of an insole.

2. A shank stiffener comprising a resilient outer member, curved to conform to the normal curvature of the shank portion of an outsole, and provided in its forward end with a slot, adapted to have a sliding engagement with a securing member fixed to an insole; and a resilient inner member having a more abrupt curvature than the outer member, and bearing at its end portions on the outer member, said inner member being spaced, between its end portions, from the outer member, and headed rivets fixed to one of the members and passing through the end portions of the other member, one of said members being slotted to permit independent flexure of each member, so that the outer member is adapted to conform independently to flexures of the shank portion of the outsole; and the inner member constitutes an independently flexible yielding support for the shank portion of an insole.

In testimony whereof I have affixed my signature.

ALFRED T. BALCH.
